(57) **CLAIM**

The ornamental design for a color pick pen, as shown and
described.

DESCRIPTION

FIG. 1 is a perspective view of the color pick pen showing
my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof when the cap is detached
from the color pick pen.
The broken lines shown in the drawings are included for the
purpose of illustrating portions of the color pick pen that
form no part of the claimed design.
